(57) CLAIM

The ornamental design for a garment with stylized letters and design, as shown and described.

DESCRIPTION

FIG. 1 is a front view of a garment with stylized letters and design, showing my new design; and, FIG. 2 is a back view thereof.

The dashed lines in the drawings represent portions of the article which form no part of the claimed design.

The broken line showing of a shirt and the text "logo" is for the purpose of illustrating portions of the article and forms no part of the claimed design.

1 Claim, 2 Drawing Sheets
